United States Patent Office.

CHARLES M. THIELCKE, OF CHICAGO, ILLINOIS.

Letters Patent No. 106,890, dated August 30, 1870.

IMPROVED CURTAIN-FIXTURE.

The Schedule referred to in these Letters Patent and making part of the same.

To all whom it may concern:

Be it known that I, CHARLES M. THIELCKE, of Chicago, in the county of Cook and State of Illinois, have invented new and useful Improvements in Curtain-Fixtures; and I do hereby declare the following to be a full, clear, and exact description thereof, which will enable others skilled in the art to which my invention appertains to make and use the same, reference being had to the accompanying drawing forming part of this specification.

The figure is a perspective view of a curtain applied to a window in accordance with my improvements.

My invention has for its object to improve the operation of window-curtains, whereby the tension of the operating-cord is preserved under all circumstances, and the curtain prevented from being wound unevenly upon the operating-roller.

The invention consists in the combination of a guiding-wire, for the lower curtain-stick, and a spiral spring for preserving the tension of the operating-cord, as will be hereinafter more fully described.

In the accompanying drawing—

A is the window-casing, and

B is the curtain, hung to the casing upon brackets C.

D is the operating cord, passing over one grooved pulley E, secured to the end of the upper curtain-roller, in the usual manner.

F is a spiral spring, secured, at its lower end, to the window-casing by means of a screw or nail, having a removable head, G. I prefer to employ an ordinary picture nail.

The upper free end of the spring may also be pro-

vided, if desired, with a stud, having a removable head, E, around which the operating cord passes, as shown in the drawing.

By this arrangement, the tension of the operating cord is preserved under all circumstances, while the spring, being free at one end, is always in a line with the cord, and prevents the latter from casually slipping off the grooved pulley E of the curtain-roller.

By unscrewing the heads G, the spring is readily removed from the casing and cord, for a change of location, or the substitution of a new spring.

H is a wire or cord, extending along the side of the casing, parallel to the edge of the curtain, to receive an eye, I, in one end of the curtain-stick J, as shown.

This wire is held out from the casing, to permit the free vertical movement of the end of the curtain-stick by means of small eyes, K, by which, also, said wire is attached to the casing.

By this arrangement the curtain is guided in vertical lines, and prevented from slipping off either end of the roller during its operation.

Having described my invention,

What I claim as new, and desire to secure by Letters Patent, is—

The guiding-wire H and the spiral spring F, provided with the nail or stud, having a removable head, G, in combination with the curtain, its rollers, and sticks, and the operating cord, as herein shown and described, for the purpose specified.

C. M. THIELCKE.
